CONTROL VALVE MECHANISM FOR PNEUMATIC DRILLS

Filed Nov. 14, 1932

FIG. 1

FIG. 2

By A. B. Bowman

Attorney

UNITED STATES PATENT OFFICE

1,934,927

CONTROL VALVE MECHANISM FOR
PNEUMATIC DRILLS

Charles A. Hultquist, Los Angeles, Calif.

Application November 14, 1932
Serial No. 642,548

6 Claims. (Cl. 121—28)

My invention relates to control valve mechanism for pneumatic drills, and the objects of my invention are:

First, to provide a mechanism of this class in which a single slide valve controls both the inlet and exhaust ports connected with both ends of the cylinder; the valve and its casing being so arranged that the quantity of air admitted is metered, yet ample port area is available for efficient discharge of the exhaust;

Second, to provide a mechanism of this class which, although the incoming air is metered, is so arranged as to reduce the frictional losses occasioned by such metering to a minimum;

Third, to provide a mechanism of this class wherein a central inlet port is provided which acts with a slide valve adapted to direct the incoming air to one side or the other, the port and valve being so arranged that a bearing surface is provided at all times at both sides of and contiguous to the inlet port;

Fourth, to provide a valve mechanism of this class which is particularly simple and economical of manufacture; and,

Fifth, to provide on the whole a novelty constructed control valve mechanism for pneumatic drills which is durable, efficient in its action, and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a longitudinal sectional view of a control valve mechanism, parts and portions in elevation, and showing adjacent portions of a pneumatic tool fragmentarily; Fig. 2 is a transverse sectional view through 2—2 of Fig. 1; and, Fig. 3 is another transverse sectional view through 3—3 of Fig. 1.

Like characters of reference refer to similar parts and portions throughout the views of the drawing.

Valve casing 1, valve liners 2, slide valve 3, and cap members 4 constitute the principal parts and portions of my novel control valve mechanism for pneumatic drills.

The parts of the pneumatic drill particularly associated with my control valve mechanism are a cylinder A closed at one end by a head member B, and at the other end by a sleeve member C through which extends the shank D of a piston E mounted within the cylinder A.

Secured to one side of the cylinder A is a valve casing 1 which is provided with a bore 1a

therethrough paralleling the bore of the cylinder A. A valve liner 2 is fitted in the bore 1a from each end of the valve casing 1. Each liner 2 is hollow and comprises a cylindrical portion 2a and a flanged head portion 2b which fits against the corresponding end of the casing 1. The inner extremities of the liners 2 are spaced from each other forming an annular inlet port 2c which registers with an inlet slot 1b in the wall of the casing 1. The slot 1b intersects an internally threaded boss 1c into which the air supply line is connected.

The bores of the liners 2 which are coaxial slidably receive a slide valve 3. The movement of the slide valve 3 is limited by a cap or head member 4 which plug the ends of the valve liners and are secured therewith to the casing 1.

The bore of the casing 1 is provided with a series of annular grooves 1d, 1e and 1f arranged outwardly at either side of the slot 1b.

The innermost pair of channels 1d are intersected by passages F and G which extend into the wall of the cylinder A, then along the wall to opposite ends of the cylinder where they intersect the interior thereof. These passages alternately form the intake and exhaust ports of the cylinder A. The liners 2 are provided with groups of annularly arranged slots 2d and 2e and an annular group of holes 2f registering with and corresponding to the channels 1d, 1e and 1f.

The bores of the liners are of equal diameter and are constant throughout except for enlarged portions adjacent the axial inner ends of the liners which together form the inlet port 2c. The sleeve valve 3 comprises a central disc member 3a which forms a close sliding fit with the enlarged portions of the bores and has an axial extent greater than the inlet port 2c so that the disc 3a bears on both sides of the inlet port at all times. At each side of the central disc 3a the slide valve is reduced in diameter forming a pair of relatively deep annular channels 3b. The channels 3b are bordered at their axially outward sides by annular flanges 3c which fit snugly in the smaller diametered or normal portions of the bores. The weight of the slide valve may be decreased by providing additional grooves or channels 3d between the flanges 3c and extremities of the sleeve valve. In such case the sleeve valve is provided at its extremities with bearing flanges 3e. The end faces of the sleeve valve are provided with small bosses 3f which form with the inner ends of the caps 4 small chambers for the admission of air used to shift the sleeve valve, as will be described hereinafter.

In each side of the central ridge or disc 3a are cut a pair of notches 3g. The notches are so arranged that either one pair or the other register with the intake ports 2c and form with the axially inner extremities of the liners meter 115

110

115

120

valves adapted to regulate the quantity of air admitted. The movement of the slide valve is restricted so that the channels 3b do not register directly with the intake port 2c therefore the air 5 flows axially through the meter valves formed by the notches 3g. After the valve shifts so that the capacity of the communications between the intake port 2c and the notches 3g is equal to or exceeds the capacity of said meter valves, further 10 axial movement of the slide valve within its stroke does not vary the flow through said meter valves. Hence, the valve ports may be made relatively large, limited only by the axial extent of the notches 3g and stroke of the slide valve.

15 When either of the channels 3b are in communication with the intake port 2c through the notches 3g, the incoming air flows through the intake port 2c, through the channels 3d out through corresponding slots 2d into the corresponding 20 grooves 1d, whereupon the air passes into either the passage F or G. When one channel 3b is functioning to connect its passage with a source of air supply, the other channel 3b connects the remaining groove 1d and its passage 25 F or G with the adjacent groove 1e. The grooves 1e intersect the side wall of the casing 1 and constitute outlet ports.

The remaining or outermost grooves 1f are connected with passages H and I which cross but 30 do not intersect each other and communicate with the cylinder A near its central portion. These passages conduct air from the cylinder to the ends of the sleeve valve so as to shift the valve from one extreme position to the other.

35 Though I have shown and described a particular construction, combination and arrangement of parts and portions, I do not wish to be limited to this particular construction, combination and arrangement, but desire to include in 40 the scope of my invention the construction, combination and arrangement substantially as set forth in the appended claims.

Having thus described my invention, what I 45 claim as new and desire to secure by Letters Patent is:

1. In a control valve mechanism for pneumatic drills, a casing having a bore therethrough, an annular intake port surrounding and intersecting said bore, and other ports also intersecting 50 said bore, a slide valve mounted in said bore, including a disc bridging said intake port so as to bear on both sides thereof, channels at either axial side thereof for linking the several ports, and spaced apart metering notches formed in the 55 sides of said disc for communicating with said intake port and arranged to direct air therefrom axially into either of said channels.

2. In a control valve mechanism for pneumatic drills, a casing, having a bore therethrough, a 60 pair of tubular liners positioned in said bore and terminating with their inner ends in contiguous but spaced relation forming an annular intake port, said liners having other ports intermediate their ends, a slide valve mounted in said liners, 65 including a disc bridging said intake port so as to bear on both sides thereof, channels at either axial side thereof for linking the several ports, and spaced apart metering notches formed in the sides of said disc for communicating with 70 said intake port and arranged to direct air therefrom axially into either of said channels.

3. In a control valve mechanism for pneumatic drills, the combination with a casing having a

bore and a plurality of ports, including an intake port, therein communicating with the cylinder of a pneumatic drill so as to effect operation of a hammer or piston therein, a slide valve mounted in said bore, including a disc bridging said intake port so as to bear on both sides thereof, channels at either axial side thereof for linking the several ports, and spaced apart metering notches formed in the sides of said disc for communicating with said intake port and arranged to direct air therefrom axially into either of said channels.

4. In a control valve mechanism for pneumatic drills, the combination with a casing having a bore and a plurality of ports, including an intake port, therein communicating with the cylinder of a pneumatic drill so as to effect operation of a hammer or piston therein, a pair of tubular liners positioned within said bore and terminating with their inner ends in contiguous but spaced relation forming an intake aperture registering with said intake port, said liners provided with other apertures registering with the other ports, a slide valve mounted in said liners, including a disc bridging said intake port so as to bear on both sides thereof, channels at either axial side thereof for linking the several ports, and spaced apart metering notches formed in the sides of said disc for communicating with said intake port and arranged to direct air therefrom axially into either of said channels.

5. In a control valve mechanism for pneumatic drills, the combination with a casing having a bore and a plurality of ports therein communicating with the cylinder of a rock drill so as to effect operation of a hammer or piston therein, and tubular liners inserted in the bore wherein the liners have apertures registering with the several ports, of a slide valve mounted in said tubular liners, having a disc portion adapted to register with and bridge the aperture and corresponding port forming the intake, annular channels on either side of said disc arranged to connect adjacent ports, and notches formed in the axial sides of said disc arranged to form a communication between said intake port and one or the other of said channels.

6. In a control valve mechanism for pneumatic drills, the combination with a casing having a bore and a plurality of ports therein communicating with the cylinders of a rock drill so as to effect operation of a hammer or piston therein, of a pair of liners adapted to be inserted in the bore with their inner ends in spaced relation forming an intake aperture, each of said 130 liners being tubular having a larger diametered portion at its inner end, and a smaller diametered portion outwardly therefrom and intersected by other apertures, said apertures registering with the ports in said casing, a cylindrical slide valve 135 mounted therein including a central disc arranged to fit the larger diametered portions of the liners and bridge the intake aperture formed therebetween, and discs arranged to fit the smaller diametered portions of the liners, there being formed between said discs a pair of channels adapted to connect adjacent apertures, and notches in the sides and periphery of said central disc arranged to uncover one side or the other of said intake aperture for directing the 145 air axially into one or the other of said channels.

CHARLES A. HULTQUIST.
